UNITED STATES PATENT OFFICE.

WILLIAM KUPKE, OF CHICAGO, ILLINOIS.

RAIL LOCK.

Application filed June 14, 1926. Serial No. 115,862.

My invention relates to improvements in rail locks, and has for its object a provision of an improved construction of this character by means of which adjacent rail ends at the joints or gaps therebetween, may be securely and positively locked together so as to in effect constitute a continuous rigid construction, which is capable of economical manufacture and highly efficient in use.

10 Other objects will appear hereinafter.

The invention consists in the combinations and arrangements of parts hereinafter described and claimed.

15 The invention will be best understood by reference to the accompanying drawings forming a part of this specification, and in which,

20 Fig. 1 is a top plan view, shown partially in horizontal section, of a rail lock or joint embodying the invention;

Fig. 2 is a side view of the same;

Fig. 3 is a transverse section taken through the rail adjacent said joint;

25 Fig. 4 is a top plan view of one of two complementary locking parts;

Fig. 5 is a side view corresponding with Fig. 4; and

Fig. 6 is an end view corresponding with Fig. 5.

30 The preferred form of construction as illustrated in the drawings comprises two identical complementary parts each consisting of a main base plate 7 adapted and arranged to rest under the base of a railroad rail and provided at opposite sides with perforated lugs 8 for the reception of spikes to secure the same to the ties. Each main base plate 7 is provided at one side with a longitudinal projection 9 of a width substantially equal to one-half of the width of the base of the rail, thus leaving a gap or recess 9' for the reception of the corresponding extension 9 on the complementary part. Each main base plate 7 is also provided at 35 its edge opposite the extension 9 with an upwardly and inwardly extending lip or shoe 10 adapted to engage under the corresponding side of the head of the rail as shown. Each shoe 10 is provided with a longitudinal extension 11 of the same length as the extension 9 and adapted and arranged 40 to constitute a side plate resting flat against the corresponding side of the rail. Each extension 11 is provided with bolt holes 12 and a slot 13 as shown.

50 In use two of the parts thus provided are

oppositely arranged at each rail joint as shown, with the extensions 9 interlocking laterally with each other and constituting a complete level support for the base 14 of the rails with the extensions 11 resting flat against the sides of the webs 15 of the rails, and with the shoes 10 resting against the corresponding undersides of the rail heads 16 as shown. Bolts 17 are passed through the holes 12 and the slots 13 thus securing the rail ends rigidly together but the slots 13 permitting sufficient longitudinal movement to take care of expansions and contractions of the rails, the parts being securely spiked to the ties by means of the lugs 8. By this arrangement a simple and effective rail lock or joint is provided which will securely and rigidly join the ends of the rails and it is economical in manufacture and highly efficient in use. The specific form and arrangement of parts is a simple and effective one for the purpose.

55 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

60 Having described my invention, what I claim as new and desire to secure by Letters Patent is:

1. A device of the class described comprising two complementary parts, each part comprising a base plate to rest under a rail and a side plate spanning the gap between adjacent rail ends; lateral enlargements connecting the base plate and side plate and contacting with the ball and web of the rail to reinforce the latter at the point of connection of a pair of rail sections, bolts securing 65 said side plates to said rail webs, substantially as described, a longitudinal extension formed on each of the lateral enlargements offset from the latter so that they will lie against the web of the rails, and fastenings 70 passing through the longitudinal extensions and railway webs.

75 2. A device of the class described comprising two complementary parts, each of said parts comprising a main base plate 110 adapted to rest under a rail and provided at side with perforated lugs for the reception

of spikes; a longitudinal extension on each base plate substantially equal in width to one-half of the width of the base of the rail and adapted to rest under the corresponding 5 half of said rail base; an upwardly and inwardly inclined shoe at the side of said base plate opposite said longitudinal extension, said shoe being adapted and arranged to engage under the corresponding head of the 10 rail; a longitudinally extending extension on the edge of said shoe adapted to rest flat against the corresponding side of the rail web, said extension being of substantially the same length as said base plate extension 15 and perforated for the passage of bolts, two of said complementary parts being arranged at a rail joint to span the gap between adjacent rail ends, with said longitudinal base plate extensions interlocking with each 20 other laterally and said shoe extensions resting against opposite sides of the rail webs; and bolts passed through said shoe extensions and said rail webs on opposite sides

of the joint gap, substantially as described. 3. The combination with the meeting ends 25 of a pair of rail sections, of means for connecting and reenforcing such sections at their meeting ends comprising a pair of base plates upon which the rail ends are adapted to rest, an upwardly inclined lateral enlargement carried by each base plate at the 30 opposite sides of and engaging the rail sections at the opposite faces of their webs and contacting with the underface of the rail heads, a forwardly extending longitudinal 35 extension formed on each of the enlargements and offset from the latter whereby they are disposed against the face of the web of the rails and bridge the joint, and removable fastenings extending through 40 such longitudinal extensions and the rail sections.

In testimony whereof I have signed my name to this specification.

WILLIAM KUPKE.
